UNITED STATES PATENT OFFICE.

DE WANE B. SMITH, OF DEERFIELD, NEW YORK.

COLLAR ATTACHMENT FOR DOUBLE HARNESS.

SPECIFICATION forming part of Letters Patent No. 316,842, dated April 28, 1885.

Application filed August 8, 1884. (No model.)

To all whom it may concern:

Be it known that I, DE WANE B. SMITH, a citizen of the United States, and a resident of the town of Deerfield, in the county of Oneida and State of New York, have invented a new and useful Improvement in a Neck-Yoke and Balanced Collar-Draft; and I do hereby declare the following to be a full, clear, and exact description of the same, reference being had to the accompanying drawings, and to the letters and figures marked thereon.

My invention relates to a neck-yoke and balanced collar-draft; and it consists in the mechanism hereinafter more fully described and claimed.

In the accompanying drawings, Figure 1 represents a side view of my improved balanced collar-draft, taken at line x x , Fig. 2, showing the angle in the balanced collar-draft, 20 upper, lower, and central connection, the vertical support, and draft-connection. Fig. 2 is a front view of my improved balanced collar-draft, showing collars and hames of a harness, balanced draft-collars, upper and lower draft-bars, and vertical support. Fig. 25 3 is a top view of the bottom adjustable draft-bar. Fig. 4 is a cross-section taken at line x y , Fig. 3. Fig. 5 is a bottom view of the upper draft-bar. Fig. 6 is a cross-section view 30 of the same, taken at line e f , Fig. 5. Fig. 7 is a front view of my improved balanced draft-collars pivoted to the hames of an ordinary harness. Fig. 8 is a side view of my improved balanced draft-collars, showing the 35 relative shape of the same and the flexible connection with the hames.

Having described my invention by reference to the figures in the accompanying drawings, I will now proceed to describe it by reference to the letters marked thereon, in which 40 similar letters refer to corresponding parts throughout the several views.

A represents a circular balanced draft-collar with an obtuse angle about the center, as indicated in Fig. 8.

a represents a slot or loop in the upper portion of the draft-collar for the reception of a strap or other means of connection.

a' represents a similar one in the lower portion of the same.

a^2 a^2 represent an adjustable pivotal connection between the sides of the draft-collar

and the hame of a harness to accommodate the motion of the horse to the load in drawing, holding back, or turning. This is so located as to bring the draft, when applied in the right place, on the hame or collar.

H represents the hames of a harness.

B represents a lower draft-bar and neck-yoke. Each end of this draft-bar is attached 60 to the draft-collars at a' a' , Fig. 2, by adjustable connections b b , connected at the ends of the draft-bar b' b' . This bar should be provided with means of lateral adjustment to properly adjust the draft of the team when at 65 work.

B' represents the top draft-bar. The extreme ends of this bar are attached by a flexible adjustable connection with the top of the draft-collars at a a , by means of flexible and 70 adjustable connections b^2 b^2 . Means of lateral adjustment of this connection are provided at b^3 b^3 to accommodate unequal drafts of the horses.

e represents a connecting-cable, one end 75 provided with links or suitable means of adjustment.

e' represents the adjusting-links, which are attached to the upper draft-bar by hook e^2 .

e^3 represents the lower cable, provided with 80 a similar means of adjustment.

e^4 represents the hooks on the lower draft-bar connecting with the lower cable.

e^5 represents the rigid union of the two cables to effect the required position of the draft 85 on the draft-collars. An upward, downward, and lateral motion is secured to the yoke by means of the cables and their adjustment, the cables being so adjusted as to locate the draft at the point of the union of the collar-drafts and hames.

C represents a vertical support between the upper and lower draft-bars of such length as to keep the two draft-bars extended to prevent the same from striking the horses. The 95 extreme ends are held or pivoted to the draft-bars. I prefer the connection to be flexible.

h represents a neck-yoke ring. I prefer in using this neck-yoke with a pole to have two vertical supports to permit upward and downward motion.

P represents the pole or tongue.

Operation: The balanced draft-collars are pivoted by a flexible joint to the hames of the

harness at the place where the tug-holders are usually secured to the hame to allow an adjusting forward, backward, and lateral swing to the circles. The lower and upper draft-bars 5 are each attached by a flexible and adjustable connection with the upper and lower parts of the collars. A vertical support is placed between the upper and lower draft-collars and jointed either rigidly or flexibly 10 to the draft-bars. I prefer that the connection be flexible. The connecting Y-shaped cables are attached to a central ring on the upper and lower draft-bars and the opposite end to the vehicle or load, and adjusted to accommodate the balanced collar-draft to the 15 load and the horses. By the adjustment of the cable the center of the draft is at the point of union of the collar-drafts and the hames, leaving the balanced collar-drafts at liberty 20 to move upward, downward, or laterally when turning, backing, or drawing. The angle in the draft-collars admits of a forward, backward, and side motion when on the horses without coming in contact with them. 25 What I claim as new, and desire to secure by Letters Patent, is—

1. The herein-described neck-yoke, consisting of a pair of balanced draft-collars, bent as described, and attached on each side

at or near the angle of the bent portion to the 30 hames of a harness to secure a direct and lateral motion of the same, an upper and lower draft-bar secured at each end to the upper and lower portions of the collars, a vertical support between the draft-bars for keeping 35 the same separated, and flexible connecting-straps with the upper and lower draft-bars, substantially as described.

2. A neck-yoke consisting of a pair of balanced draft-collars, bent as described, and attached on each side at or near the angle of the bent portion to the hames of a harness to secure a direct and lateral motion of the same, an upper and lower draft-bar secured at each end to the upper and lower portion of 40 the collars, a vertical support for keeping the draft-bars separated, in combination with two draft-cables rigidly joined at or near their longitudinal centers and adjustably attached to the upper and lower draft-bar, as de- 45 scribed, for the purposes stated.

Signed at Utica, New York, this 6th day of August, 1884.

DE WANE B. SMITH.
